UNITED STATES PATENT OFFICE

160,794

TOY MOUSE

Benjamin L. Levinson, New York, N. Y., assignor
to Electric Animals, Inc., New York, N. Y., a
corporation of New York

Application March 22, 1950, Serial No. 8,685

Term of patent 14 years

(Cl. D34—2)

To all whom it may concern:

Be it known that I, Benjamin L. Levinson, a citizen of the United States and residing in the city, county, and State of New York, have invented a new, original, and ornamental Design for a Toy Mouse, of which the following is a specification, reference being had to the accompanying drawing, forming a part thereof, in which:

Fig. 1 is a perspective view of a toy mouse, showing my new design;

Fig. 2 is a side elevational view thereof;

Fig. 3 is a front elevational view thereof; and
Fig. 4 is a rear elevational view thereof.

I claim:
The ornamental design for a toy mouse, as shown.

BENJAMIN L. LEVINSON.
